CLAIM

The ornamental design for a storage container, as shown and described.

DESCRIPTION

FIG. 1 is a front perspective view of a storage container showing my new design with the doors in an open position;

FIG. 2 is a side elevational view with the doors in a closed position;

FIG. 3 is a top plan view thereof;

FIG. 4 is a bottom plan view thereof;

FIG. 5 is an end elevational view thereof; and,

FIG. 6 is an opposite end elevational view thereof.
